Specification of Letters Patent.

Patented Dec. 9, 1913.

Application filed May 21, 1909. Serial No. 497,397.

To all whom it may concern:

Be it known that we, GEORGE DE FEVRE, a citizen of the Republic of France, residing in the borough of Manhattan, city, county, and State of New York, and JAMES E. WOODBRIDGE, a citizen of the United States, residing in the borough of Manhattan, city, county, and State of New York, have invented a new and useful Improvement in Automobiles, of which the following is a description.

This invention has reference to automobiles and, particularly, to radiators for internal combustion engines.

This invention also relates to a novel arrangement of radiator or condenser, fan and hood on the frame or chassis of automobiles.

Among the objects of our invention may be noted the following: to provide an arrangement and disposition of the hood, radiator and fan which will protect the radiator and increase its efficiency; to provide an arrangement and construction of the hood and radiator which will protect the motor and render it readily accessible from all points and not detract from the efficiency of the radiator; to provide means by which the air may be drawn into the face of the radiator and exhausted from the latter practically in all directions; and to provide means by which the radiator can be prevented from becoming overheated.

With the above objects in view, and others which will be detailed during the course of this description, our invention consists in the parts, features, elements and combinations of elements, all as hereinafter described and claimed.

In order that our invention may be clearly understood, the accompanying drawings are provided in which:

Figure 1 is a partial elevation and longitudinal, vertical section of the forward end of the frame or chassis of an automobile having our invention applied thereto; Fig. 2 is a perspective view illustrating the dashboard, side-bars and radiator, according to our invention; Fig. 3 is a view similar to Fig. 1 showing a portion of the hood in side elevation; Fig. 4 is a vertical, transverse section taken on the line 4-4 of Fig. 3; and Fig. 5 is a section taken on the line 5-5 of Fig. 3.

Referring to the drawings, the numeral 1 indicates the side-bars of the frame or

chassis of an automobile; 2 the dashboard of the car; and 3 the motor, which is supported in the usual manner upon the frame 1, the motor being shown in outline merely and without reference to details, since it may be of any approved type. In the form shown in Figs. 1 and 2, the hood 4, which covers the motor, is hinged at 5 to the face-plate 6 of the radiator-frame above its radiating section 7, the said radiator being thus arranged between the rear end of the hood and the front of the dash-board 2 and secured to the latter by means of the side and top flanges 8, which are provided with a series of apertures through which and the dash-board bolts 9 are passed to fasten it firmly to the latter, the radiator setting at its bottom on the opposite side-bars 1 of the frame to which it is also securely bolted. At its forward end, the hood may be secured or latched to the frame in any usual manner, so as to prevent it from rattling or being lifted, and in its forward face is provided with a door or gate composed of a rectangular frame 10, provided with a screen 11, and hinged at its bottom, as at 12, near the lower edge of the front end of the hood, a lock or latch 13 being provided to secure the same against accidental opening or to prevent any one from opening it without a key. As shown in Figs. 1 and 2, the hood extends vertically from the frame of the car to near the top of the radiator and laterally covers a large portion of the tubing of said radiator. This feature is shown particularly in Fig. 2, where the outline of the hood is represented by dotted lines. Thus, outside of the frame of the hood, large volumes of air can be drawn into the face of the radiator at opposite sides, while a very large volume of air can be drawn in through the screen 11 at the front end of the hood and around the motor, thus rendering effective the entire face of the radiating section of the radiator. We desire to lay particular stress upon the disposition of the radiator in the rear of the hood and remote from the front end of the car since it gives great protection to the radiator, which is a comparatively delicate and expensive element of the car. Furthermore, this arrangement gives symmetry and an esthetic appearance to the car, which is very desirable.

The radiator, in its general features, may be of any usual form, though we prefer that

form which is illustrated in our application Serial No. 491,301, filed April 21, 1909. The radiator, according to our present invention, will have the top portion 14 of its frame extended rearwardly quite a distance beyond its side frame-portions 15 and the radiating section 7, as clearly shown in Fig. 1; and, corresponding to this frame extension 14, the opposite sides of the frame of the radiator are provided with the screen-sections 16, which leave the frame of the radiator practically open at both sides in rear of its radiating-section. This structure of the frame provides a large chamber 17 between the dash-board 2 and the radiating-section 7, and between the frame-portion 14 and the side-bars of the chassis. The top frame-portion 14 is provided with a plurality of apertures or slots 18, arranged in a series extending substantially from side to side of the radiator; and the bottom of the chamber 17 is entirely open, since the framing is omitted in the space 19, between the side-bars 1 of the chassis. Furthermore, the dash-board 2 is cut out at its bottom across substantially its entire width, so as to provide the passage 20 at the back of the chamber 17, near its bottom, which communicates with the space 21, under the foot-board 22 of the car, thus continuing the chamber 17 through the dash-board and under the foot-board. No bottom-piece is provided in the space 19, between the side-bars of the chassis directly under the foot-board 22 and dash-board 2, thus allowing the air drawn into the radiator by the fan 23 to pass and to be forced through the chamber 17 into the space 21 and down through the bottom of the car under the foot-board 22, as well as down through the bottom of the chamber through the space 19, and laterally through the screen 16 in the opposite sides of the radiator, and also through the apertures 18 in the top part 14 of the radiator-frame. The fan may be of any usual construction suitable for the purpose of drawing air into the chamber 17 through the face of the radiator and at the same time acting to drive or force the air from said chamber all around, as just described. The fan preferably is located within the chamber 17, directly behind the radiating-section 7, and is journaled at 24 to the dash-board. The fan-frame is provided with the pulley-extension 25, around which runs the belt 26, which latter is driven in usual manner by the drive-wheel 27 of the motor, or by any other available mechanism of the car. At this point, we desire to lay stress upon the general arrangement and combination of parts just described, in that it is an important feature of our invention to provide the chamber 17 in rear of the radiator and have the fan located in said chamber directly behind the radiating-section, so as to enable the fan to

provide a powerful exhaust through said tubing and operate to powerfully drive the air thus drawn into the chamber 17 from the latter in all directions. It is to be understood, however, that the disposition of the fan-pulley shown is not to be taken as essential, for said pulley could be disposed at the back of the fan so as to be between the latter and the dash-board.

Preferably, the screen-sections 16 are made removable, the means shown in this instance being lugs 28 on the side-bars 1 of the frame of the car for confining the lower end of the screen-section, and a latch 29 at the top for holding the upper end of the screen-section firmly in place. By swinging the latch away from the screen-section 16, it can be readily lifted from the confining lugs 28. No stress is laid upon the particular means for rendering the screen-sections removable, though importance is attached to the removability of said sections, since it enables ready access to the fan and to the radiator in case of accident, or if for any purpose it is desired to gain access to the chamber 17.

In the form of our invention shown in Figs. 3, 4 and 5, the hood 4 is made with an inner casing 30, which, in form, may or may not conform to the outline of the engine-cylinders and inlet-pipes, this casing being connected at 31 to the hood 4, near its hinged end, and at its lower end is secured all around to the lower edge of the hood, thus providing between the hood and the casing 32 a chamber 33. By thus constructing the hood, the same is made double, and upon this feature of our invention we desire to lay stress, since its importance lies in the fact that the hood 4 can be made of substantially any shape desired for ornamental purposes and with a view to giving symmetry and esthetic form to the car at its forward end, and can also be provided with openings of any character desired at front and sides calculated to freely admit air in large volume for transmission to the radiating-section of the radiator. This structure has a great advantage also in that a sealed-hood effect is obtained, in combination with an open-hood effect, since it is quite desirable to prevent sand, grit, dust, water, or other substances from reaching the cylinders of the motor, or other parts thereof, and it is also essential to admit as much air to the hood as possible, in order to supply the required great volume of air for cooling purposes. Furthermore, by providing the inner sealed-hood, the outer hood can be provided with all kinds of openings or air-flues, such as the screen 11 and air-inlets, and the elongated, vertical slots 33, in rear of each of which a fin 34 may be provided, which will effectively catch and shunt the air into the chamber 32, thus increasing the volume of air passing 130

to the radiator-tubes. In other words, the double-hood described completely protects the motor and, at the same time, furnishes the largest possible supply of cool air to the radiator. Moreover, the motor is kept cool, or prevented from becoming overheated, by leaving between the same and the inner sealed-hood the largest possible space; that is to say, the inner-hood is made to follow the contour of the outer-hood or the contour of the motor, and, in either case the motor-chamber is made as large as possible and the hood-chamber as narrow as possible.

Obviously, when it is desired to inspect the motor, or get at the mechanism under the hood, the latter can be lifted and, in the form shown in Figs. 3, 4 and 5, the inner sealed-hood will be lifted at the same time, since the outer and the inner hoods are connected together. This is exceedingly important since, when it is necessary to inspect or examine the motor, it should be possible to gain access to every part from every side. This is possible in our construction on account of placing the radiator in rear of the hood as described. The inner sealed-hood prevents the dust, dirt, grit, sand and rain from reaching the cylinders, or any operative parts of the motor and, in consequence, the latter will be kept perfectly clean and the usual wear and tear on it will be eliminated. By providing the inner sealed-hood as described, the usual fins or shutters, which guard the side openings in the outer hood, can be omitted, since rain, dust, etc., cannot reach the motor but will pass through the chamber 32 and the radiator and be ejected from the bottom of the car and the sides and top of the radiator.

From the foregoing description, it will be seen that the following are among the advantages of our invention: The radiator is completely protected from all possibility of accidental damage, since it is so far back from the front of the car as to eliminate all chance of vehicles striking the same, or of its being injured if the car should strike obstructions of any kind, or moving objects of any character, this being important since repairs to radiators are usually very expensive and accidents to the radiator are liable to put it and the car out of commission. The disposition shown of the radiator also places it back of the motor and makes the latter much more accessible from every point when necessary to work on it for any purpose. This is exceedingly important since it enables thorough examination and quick repairs. By disposing the radiator as shown, in combination with a hood such as shown, the range of vision of the operator or driver of the car is very much increased, since the road ahead close to the front of the vehicle is clearly in sight and enables small objects to be quickly seen and avoided. This is especially important when the car is going at high speed and small objects are not readily discernible until the car is almost upon them, and often cannot be seen at all when the car has a high projection such as made by the radiator placed at the front end of the car in the line of vision. By placing the fan directly behind the radiating-section, the air can be drawn in freely through said section and quickly forced out of the top, sides and bottom, thus quickly disposing of the hot air and increasing the cooling efficiency of the radiator. By making the hood double, it is also considerably strengthened and rendered much more rigid than a single hood, thus avoiding warping and springing of the side and ends and maintaining it always in good condition and capable of being fastened down tight to insure the engine from grit, dust, etc. We desire it understood, however, that we do not purpose limiting our invention to any particular form of radiating-section, as it is within the scope of our invention to employ any form of radiator-tubing found efficient and practicable for the purpose. Nor do we purpose confining our invention to the disposition of the fan in the chamber in rear of the tubing, though this disposition is preferable, since the fan could be placed in front of the tubing in the hood-chamber and so formed as to force the air through the tubing. Moreover, we do not purpose limiting our invention to driving the air from the chamber 17 through the sides, top, bottom and back, as illustrated and described, since there may be forms of cars necessitating the elimination of some of the outlets and restricting the exhaust to the sides or the top, or the bottom, or the back, or any two or more ways of forcing the air from the chamber.

Having thus described our invention, what we claim and desire to secure by Letters Patent is:

1. In a cooling apparatus for automobiles, the combination with a motor, a casing covering said motor and completely hooding the same, a cooling device coöperating with the rear end of said casing and having a portion of its radiating-section exposed and a portion covered by said casing, a chamber in rear of said cooling device coöperating with the latter and having openings through which air entering the chamber from the cooling device may be expelled, and means located in said chamber for expelling the air from the latter and preventing the air from reaching the motor casing. 115
2. In combination with the chassis of an automobile, a motor supported by said chassis, a hood covering said motor and having means coöperating with the chassis 120

to lock the hood to the latter, a cooling device in rear of said hood having a portion of its radiating-section covered by the end of said hood and a portion exposed outside of said hood, and means in rear of said cooling device for drawing air through its radiating-section.

3. In combination with the motor of an automobile, a hood for protecting said motor comprising an inner casing and an outer casing, the casings being secured together in spaced-apart relation so as to provide an air chamber between the same and inclosing the motor in a chamber; and a radiator arranged in rear of the motor and closing the rear end of the motor chamber; and means for exhausting the heat from the motor chamber through said radiator.

4. In combination with the motor of an automobile, a hood for protecting said motor comprising an inner casing and an outer casing, the casings being secured together in spaced apart relation so as to provide between the same an air chamber; and means whereby said double hood may be lifted clear of the motor to permit inspection of the latter.

5. A motor car having in combination with its frame, motor and cooling device, a double hood covering the motor, and having a chamber through which air may pass to the cooling device and through the same without coming into contact with the motor.

6. In combination with the frame and motor of a motor car, a double hood for covering the motor and completely protecting it from grit, dust, etc., said hood having a chamber independent of the chamber in which the motor stands, a cooling device having a radiating-section coöperating with the said chamber of the hood, means whereby air may be admitted through the hood into said chamber, and means for drawing air through said chamber and the radiating-section of the cooling device and expelling it from the latter.

7. In combination with the chassis of a motor car, a motor supported on said chassis, a hood covering said motor having its rear end open and its front end closed, a cooling device having its radiating-section covering the rear open end of the hood, said cooling device having an air chamber in rear of its radiating-section, a rotary fan located in said chamber, and means whereby air drawn through the radiating-section of the cooling device may be expelled from said chamber.

8. In combination with the motor of an automobile, a cooling device arranged in rear of said motor and comprising a radiating-section and a rear extension forming a chamber, the walls of which chamber have removably secured sections provided with openings, and means within the chamber for

forcing the air therefrom through said openings.

9. In combination with the motor of an automobile, a cooling device arranged in rear of said motor and having a radiating-section and a chamber in rear thereof, said chamber being formed by side and top extensions provided with openings through which the air may be expelled, and a rotary fan having means whereby it may draw air through the radiating-section and expel the same through the said extensions of said chamber.

10. In combination with a motor car having its dash-board located remote from the end of its chassis and having the bottom of said dash-board provided with a passage extending under the foot-board of the car, a motor supported on the chassis in front of the dash-board, a cooling device located between the motor and the dash-board, means for removably securing the cooling device to said dash-board, a hood supported by the chassis and covering the said motor and a portion of the radiating-section of said cooling device, means for securing the hood in place on the car, and means for expelling air from said cooling device through the passage under the foot-board.

11. In combination with the frame of a motor car having its dash-board remote from the forward end of its chassis, and having the base of its dash-board provided with a passage therethrough, a motor supported on the chassis in front of the dash-board, a cooling-device arranged between the motor and the dash-board, means for removably securing the cooling device in place, a hood having an air receiving chamber the bottom of which completely covers said motor and said hood also covering a portion of the radiating-section of the cooling device, the chamber of said hood having a screened opening at the front of the latter and said chamber communicating with the radiating-section of said cooling device, whereby air entering said chamber cannot reach the motor.

12. In combination with the chassis of an automobile, an engine supported near the forward end of the chassis; a radiator or cooling-device disposed in rear of the engine; a hood secured to the radiator and extending around the engine, so as to inclose the same, and into coöperative relation with the chassis in front and at both sides of the engine, said hood also covering a large portion of the cooler; and means in coöperative relation with the cooler for exhausting the heat from the engine chamber of the hood and drawing cool air through the exposed face of the radiator, substantially as described.

13. In combination with the frame of an automobile, a radiator removably secured to

the dash-board of the automobile; an engine secured to the frame in front of the radiator; a hood hinged to the face of the radiator and extending about the engine; a chamber arranged between the dash-board and the radiator; and means for exhausting hot air from the hood-chamber and simultaneously drawing cool air through the face of the radiator into said chamber and expelling the cool and heated air thus drawn into the chamber from the latter.

14. In combination with the dash-board of the car, a radiator removably secured thereto having its top extended to provide a chamber

ber between its body and the dash-board, 15 and foraminous sections removably secured in coöperative relation to the sides of the radiator and the dash-board, substantially as described.

In testimony whereof we have hereunto 20 signed our names in the presence of two subscribing witnesses.
